UNITED STATES PATENT OFFICE.

VICTOR S. ALLIEN, OF NEW YORK, N. Y., ASSIGNOR TO DARCO SALES CORPORATION, OF NEW YORK, N. Y., A CORPORATION OF DELAWARE.

PROCESS OF SECURING UNIFORM REVIVIFICATION OF ACTIVATED CARBON.

Application filed July 16, 1924. Serial No. 726,288.

Particles of activated carbon which are used for the decolorizing or purification of liquids, as for instance sugar solutions, are of irregular shape, and the efficiency in operation is in part dependent upon the surface area of the particles which is exposed for action to the liquid. The rapidity with which the particles may be filtered or otherwise separated from the liquid after treatment of the latter, is in part dependent upon the state of subdivision of the particles.

It is known that activated carbon after use may be revivified by a heat treatment. The main object of my invention is to subject the particles to the heating action in such a way as to get a maximum and uniform revivifying action with the minimum loss or deterioration.

In my improved process I so treat the particles that they are progressively advanced through a series of heat zones of successively higher temperatures. In doing so I avoid abrading action which will tend to produce powdering or breaking up of the particles or the smoothing of the surfaces thereof. I absolutely prevent or carefully control the admission of air so as to avoid variable or objectionable combustion loss. I carefully control the temperature in the successive heat zones so as to permit admission of the material to a zone of the desired low temperature, and the final delivery of the material from a zone of the desired high temperature. I prevent contact of the material with the flame or gases of combustion and subject the material in comparatively thin layers to the action of heat from both above and below so as to secure uniformity of heating effect and free escape of moisture or other vaporizable substances. I conduct from each heating zone the vapors or gases without passing them through or over the layers of material in the other zones, and control the time of heat treatment in the successive heating zones by giving to the material the desired speed of travel through said zones. I so utilize the heat that I secure the maximum economy of fuel with the minimum heat loss.

My invention is not dependent upon the use of any specific form of apparatus, it only being essential that the apparatus be so designed as to permit the carrying out of the process.

In the accompanying drawings I have illustrated merely one form of apparatus which may be employed for carrying out my improved process.

In these drawings:

Fig. 1 is a central vertical section, a portion being in side elevation.

Fig. 2 is a transverse section, and

Fig. 3 is a development on the semi-circular line 3—3 of Fig. 2.

In the accompanying drawings there is shown a furnace having a central supporting structure for the material, and through which the heating gases are passed. Around this is a rotating structure which serves to advance the material, and outside of this is the stationary protecting and sealing casting. The center structure includes a series of superposed annular shelves or decks 10, each of which has a chamber 11 therein, opening to a centrally disposed vertical flue 12 through which the heating gases pass. An inner flue 13 has a series of annular baffles 14 thereon, each of which extends out into the chamber of a corresponding shelf or deck whereby the heating gases are deflected out into each chamber and may then pass back to the flue 12. In this way the material on each shelf 10 is subjected to heating effect both from above and below. The heating may be produced in any suitable manner, as for instance by a fuel burner 15 at the lower end of the flue 13, and outside of the latter, so that the lower shelf is subjected to the highest temperature and the temperature continually decreases toward the top.

To avoid pockets or dead spaces at the outer edge or periphery of each chamber 11 there is provided an annular passage 16 below the supporting surface of each shelf 10, and at the peripheries of the several annular chambers 11. The inner wall of each passage 16 has a series of apertures 16 therethrough for the passage of gases from the chamber 11 into the passage, and each passage 16 is connected to the inner flue 13 by a radially disposed conduit 17 so that the gases which pass from the chambers 11 through the openings into the passage 16, may escape directly through the conduit 17 to the inner flue 13 without being caused to pass out into the chambers 11 of the superposed shelves. By making the openings in the passage 16 of progressively in-

creasing size from adjacent the conduit 17 to a point diametrically opposite thereto, there is secured a uniform withdrawal of gas from each chamber 11 along the entire periphery thereof. Each shelf 10 has a vertical slot or opening 18 therethrough and extending radially across the entire width of the shelf so that as the material is advanced along the shelf to the opening 18 it may drop through to the shelf below. These openings 18 are so positioned in the several shelves that the material upon reaching a shelf is caused to travel along the shelf through nearly one complete revolution before it drops through to the shelf below. In other words, the openings are not in vertical alignment but are arranged in progression, each opening being slightly in the rear of the opening in the shelf above. For advancing the material along the shelves there is provided a rotatable sleeve or frame structure 19 which has a plurality of inwardly or radially extending blades 20 carried thereby and properly juxtaposed to each shelf. These blades are supported solely by the outer sleeve or frame 19, and do not rest directly upon the shelf but have a slight clearance so that they do not have any direct scraping or abrading action on the material. There are a large number of these blades for each shelf so that the material on each shelf is acted upon by a series of the blades and kept in a substantially uniform layer upon the shelf. The lower end of the sleeve or frame 19 may be supported in any suitable manner, as for instance by roller bearings 21, and may be sealed at the lower end as for instance by extending into an annular water trough 22. It may also be held in proper axial alignment with the stationary structure by means of rollers 23. Any suitable means may be employed for rotating the frame which carries the scrapers. As shown, it has a peripheral worm gear 24 which may mesh with a worm in a casing 25 and driven by a shaft 26. Encircling the rotating parts is an outer stationary casing 27 which may be made of sheet metal and air-tight. The gear casing 25 may be secured to the outer casing 27 which may have a stuffing box around the shaft 26 so as to prevent the admission of any air at this point. Above the upper shelf there is provided an annular plate 28 with a central opening communicating with the upper end of the flue 12 and an outlet flue 29 may be connected to the upper end of this flue 12 so as to conduct from the outer casing the gases of combustion. The inner flue 13 may terminate in an open end within and adjacent to the upper end of the flue 12 so that all of the gases of combustion which have passed into the inner flue 13 through the several

radial conduits 17 may unite with the other gases of combustion and escape through the flue 29.

The top of the casing may be connected to a conduit 30 through which the gases escaping from the material being treated may be drawn off to a condenser or separator, and this conduit may be connected with a vacuum pump if desired to thus subject the material to a partial vacuum during the heating action.

For delivering material to the furnace any suitable mechanism may be employed which will act to deliver measured quantities at the desired rate and prevent the admission of air. As shown, there is provided a hopper 31 delivering through a conduit 32, the lower end of which extends through the plate 28 to a point above the upper shelf 10. At the lower end of the hopper there is provided a rotatable feeding device 33 which may be in the form of a drum having pockets therein so that as the drum rotates each pocket receives material when on the upper side of the drum and delivers it from the lower side. By varying the size of the pockets in the feeding mechanism the delivery of material may be accurately controlled. The speed of rotation of the feeding mechanism should be such that a separate charge is delivered to the shelf as each blade 20 passes beneath the lower end of the conduit 32. The shaft 34 of the feed drum may be provided with a sprocket 35 which may be connected by a chain to a sprocket 36 on the shaft 26 which rotates the blades 20.

At the lower end of the furnace the material may pass from the lowermost shelf through an opening 37 to a chute 38 terminating below the surface of the water in a receiving chamber 39, and may be conducted from the latter by any suitable form of conveyor 40.

In revivifying carbon the furnace may be so controlled that the temperature at the lower shelf will be 1100° F. to 1350° F., while at the top shelf it may be about 550° F. to 600° F. The rotation of the blades should be comparatively slow, so that the material is given a gentle rolling motion without abrading action, and is advanced to shelves of successively increasing temperature. The outer stationary casing and the vertical series of shelves, permit the casing to be tapped at any points along its height for the controlled admission of steam, air or other gas to the material at any point along the path of said material, and where the material is at any desired temperature. The furnace permits of the careful admission or complete exclusion of air, as there is only one stuffing box and the remainder of the casing may be easily constructed absolutely air-tight. The gentle sweeping or rolling movement of the carbon does not

tend to abrade or powder it, and thus a final product of greatly improved character is secured.

5 The vapors or gases from each shelf or heating zone pass up along the inner surface of the sleeve without passing over the material in the zones above.

Having thus described my invention, what I claim as new and desire to secure 10 by Letters Patent is:

1. The process of revivifying activated carbon, which consists in supporting it in comparatively thin layers upon a series of superposed substantially flat and level interiorly heated shelves whereby the material is out of contact with the heating means, advancing the material in separate portions along the several shelves, and maintaining the shelves at successively higher 20 temperatures from the upper to the lower.

2. The method of securing the uniform revivification of activated carbon which includes supporting the material in a series of substantially flat and level, annular, comparatively thin superposed layers, moving the material by a gentle rolling motion in each layer in a substantially circumferential direction through nearly 360°, and then permitting it to drop to the next lower layer, 30 interiorly heating the supports to different temperatures, the lower support being heated to the highest temperature, and the heating medium being delivered to the supports in succession, and withdrawing a portion only of the heating medium from each support to prevent the delivery thereof to the next succeeding support.

3. The method of securing uniform revivification of activated carbon which in-

cludes supporting the material in a series of 40 substantially flat and level, annular, comparatively thin superposed layers, moving the material by a gentle rolling motion in each layer in a substantially circumferential direction through nearly 360°, and then permitting it to drop to the next lower layer, 45 and interiorly heating the supports to different temperatures, the lower support being heated to the highest temperature, and the heating medium being delivered to 50 the supports in succession.

4. The process of revivifying activated carbon, which consists in supporting it upon a series of superposed substantially flat and level interiorly heated shelves whereby the material is out of contact with the heating means, moving the material by a gentle rolling motion on each shelf in a substantially circumferential direction through nearly 55 360° and then permitting it to drop to the next lower shelf, and maintaining the shelves at successively higher temperatures from the higher shelf to the lower.

5. The process of revivifying activated carbon, which consists in supporting it upon a series of substantially flat, superposed, annular shelves, moving the material by a gentle rolling motion on each shelf in a substantially circumferential direction through 60 nearly 360° and then permitting it to drop to the next lower shelf, and delivering a heating medium upwardly through the interior of the said shelves in succession and 65 out of contact with said material.

Signed at New York in the county of New York and State of New York this 14th day of July A. D. 1924.

VICTOR S. ALLIEN.
